UNITED STATES PATENT OFFICE.

ANDERS ANDERSEN PINDSTOFTE, OF FREDERIKSBERG, NEAR COPENHAGEN, DENMARK.

REVOLVING BOTTLE-FILLING APPARATUS.

No. 895,191.

Specification of Letters Patent.

Patented Aug. 4, 1908.

Application filed March 13, 1907. Serial No. 362,141.

To all whom it may concern:

Be it known that I, ANDERS ANDERSEN PINDSTOFTE, manufacturer, subject of Denmark, residing at No. 62 Frederiksberg Allé, 5 Frederiksberg, near Copenhagen, Denmark, have invented certain new and useful Improvements in Revolving Bottle-Filling Apparatus, of which the following is a specification.

10 My invention relates to improvements in revolving bottle filling apparatus provided with fixed siphon-tubes and adjustable bottle-supports, and the object of my improvements is to provide means by which all of 15 such bottle-supports can be simultaneously adjusted in accordance with the bottle-size, and substantially in a direction parallel with the fixed siphon-tubes. I attain this object by the mechanism illustrated in the accompanying drawings, in which

Figure 1 is an elevation, partly in vertical section of the bottle-filling apparatus, the bottle-supports being adjusted for the filling of 1/1 liter bottles; Fig. 2 is a similar view; the 25 bottle supports being adjusted for the filling of 1/2 liter-bottles.

Similar letters refer to similar parts of the figures.

The vertical shaft *a* has its bearings in the 30 frame-work *b* and is rotated manually or by other suitable means. The vessel *c* into which the liquid to be bottled is introduced is fixed to and revolves with the shaft *a*. Said vessel is provided with a number of 35 fixed siphon tubes *d*, which near their lower end are provided with an opening *v*, through which the liquid flows from the vessel into the bottles which are inserted upon the tubes *d*.

To the support of the vessel *c* are secured 40 rods *e*, one for each of the tubes *d*. Each of the rods *e* is situated in the same vertical plane as its corresponding tube *d* and substantially parallel with it. Each of the rods *e* is provided with a slide *f*, which can move 45 freely along the rod, and which is provided with an arm *h* forming a bottle-support and a second arm *i*, the forked end of which forms bearing for a roller or the like *m*. All the rollers *m* run upon a preferably circular 50 table or plate *n*, through the center of which the shaft *a* passes, and which plate or table *n* is supported by means of a nut *o* screwed upon a screw-threaded part of the shaft *a*, so that by 55 turning the nut *o* by means of its handle *p* the plate or table *n* can be lowered or raised, thereby causing all the slides *f* to be simul-

taneously lowered or raised. Consequently all the bottle-supports *h* can be simultaneously adjusted for the filling of bottles of different size. Fig. 1 shows the bottle-tables adjusted for the filling of 1/1 liter-bottles, while Fig. 2 shows the bottle-supports adjusted for the filling of 1/2 liter-bottles.

The flow of liquid is started and stopped 65 by means of a ring-shaped member *s* (Fig. 1) which is mounted upon the filling tube and which can be moved along said tube. The downward movement of said ring-shaped member is limited by a chain *t* or the like connecting the ring-shaped member with the upper part of the filling tube. In its lower position said ring-shaped member *s* closes the opening *v* in the filling tube (see the right hand side of Fig. 1) but when the bottle is 75 inserted the ring-shaped member is moved upwards and opens the opening in the filling tube.

What I claim is:

1. In a revolving bottle filling apparatus, 80 the combination with a containing vessel for the liquid to be bottled, a revolving shaft on which said vessel is mounted, and a number of siphon tubes carried by said vessel on which the bottles to be filled are inserted; of 85 a plate or table mounted on the revolving shaft, means for adjusting said plate or table up or down, individual supports for the several bottles resting loosely and independently on the adjustable plate or table, and means 90 for guiding the individual bottle supports on lines parallel with the respective siphon tubes.

2. In a bottle filling apparatus, the combination of a revolving vertical shaft, a vessel 95 for liquid to be bottled mounted on said shaft, inclined siphon tubes carried by said vessel and on which the bottles are to be severally inserted, a vertically adjustable table mounted on the revolving shaft below said vessel, 100 separate bottle supports for the several bottles resting independently on the vertically adjustable table, and guides for the several bottle supports fixed in inclined position parallel with the several siphon tubes whereby the bottle supports are moved up or down in line with the inclined siphon tubes, substantially as described.

3. In a bottle filling apparatus, the combination of a vertical shaft, a containing vessel 110 for liquid to be bottled, mounted on said shaft, inclined siphon tubes carried by the

containing vessel and on which the bottles to be filled are inserted, a vertically adjustable plate or table mounted on the shaft, separate supports for the several bottles resting 5 loosely and independently on the vertically adjustable plate or table, and guides for the several bottle supports parallel with the respective siphon tubes, whereby the bottle

supports may be moved up and down in line with the inclined siphon tubes, as explained. 10

In testimony whereof I affix my signature in presence of two witnesses.

ANDERS ANDERSEN PINDSTOFTE.
